UNITED STATES PATENT OFFICE.

JOHN WILBER BURGETT, OF GUTTENBERG, NEW JERSEY.

SUSPENDERS.

SPECIFICATION forming part of Letters Patent No. 754,641, dated March 15, 1904.

Application filed August 15, 1902. Serial No. 119,688. (No model.)

To all whom it may concern:

Be it known that I, JOHN WILBER BURGETT, a citizen of the United States, and a resident of Guttenberg, county of Hudson, and State of New Jersey, have invented certain new and useful Improvements in Suspenders, of which the following is a specification, reference being had to the accompanying drawings, forming a part thereof, in which similar letters of reference indicate corresponding parts.

My invention relates to suspenders for men's trousers, and is more particularly in the nature of an improvement upon the novel suspenders for which I have received Letters Patent of the United States, No. 705,205, of date of July 22, 1902, in which latter case I have disclosed an arrangement which while capable of efficiently suspending the trousers will in no way interfere with the movements of the back or press upon any portion of the stomach.

In the aforesaid prior arrangement the suspenders comprise a pair of webs which pass over the shoulders and below the arms, where they are connected by rings carrying suspender-ends so disposed that they only engage with the trousers-waistband at points forward of where the hip-pockets are ordinarily located and also approximately over the points where the openings for the side pockets usually occur, the shoulder-webs being connected by a rear cross-band at such high point that while serving to relatively hold the shoulder-webs on the wearer it will in no way interfere with the free movements of the back. While such prior construction of suspenders has proved highly satisfactory, I have found that the shoulder-webs are susceptible of considerably more range of play below the arms and greater security and comfort can be secured in the connection with the trousers-waistband without in any way objectionably constricting the back and stomach. These latter results are accomplished by a novel arrangement and connection of fastening-straps, as fully appears hereinafter, and which, furthermore, are so connected with the rest of the suspenders that they may be conveniently disconnected and connected to permit the lowering and adjusting of the trousers without necessitating the removal of the coat and vest of the wearer.

In the accompanying drawings, forming part of this specification, Figure 1 is a perspective view illustrating the general arrangement and disposition of my improved suspenders when worn and viewed from a partial side and rear position. Fig. 2 is a somewhat similar view of the suspenders, showing the same on a larger scale and removed from the person of the wearer.

The shoulder-webs A A are made from lengths of strong webbing possessing a limited amount of elasticity. These webs are designed to pass over the shoulders and extend down at the rear to a point beneath the arms, where they are terminally provided with snap-hooks B.

At the front ends the webs A are provided with sliding buckles C, to each of which is attached one end of a section a of said web folded upon itself, so that it engages the buckle and slips with it on the body of the web-section in the common and well-known way to permit the section a to be adjusted as may be required. Each section a extends below the arm and carries at its lower end a snap-hook D.

The shoulder-webs A A are connected by a rear cross-band E at the high point indicated, the webbing composing the band being preferably inelastic to serve for positively holding the webs A A on the shoulders and by the absence of yielding avoid any tendency to permit said webs to slip or accidentally work sideways from the shoulders.

F F refer to the button-engaging suspender-ends, each of which presents in coactive relation the narrow cord e, having the end depending button-tabs f f² and intermediate button-tabs f' slidably arranged upon the cord to constitute a slide. The three depending button-tabs have the buttonholes f³. It will be noted that the disposition and arrangement of the cord and series of button-tabs are such that the cord at both sides of the engagement with the slide f therewith presents two open loops e e², the loops e being detachably engaged by the hook D of the coacting section a, while the loop e² is detachably engaged by the hook B, carried by the rear portion of the coacting web A. This engagement so positions each suspender-end F that

the button-tab f will engage a button g on the waistband at a point slightly in advance of where the opening of the nearest side pocket would ordinarily occur, the inclination 5 of the cord avoiding any objectionable pressure being exerted on the stomach. The intermediate button-tab f' engages a button located on the waistband in the plane of the side seam of the trousers, thereby providing 10 an extra strong connection at this point. The button-tab f'' extends at an inclination to reduce interference with the back movements and engages with a button on the waistband at a point forward of where the nearest hip-pocket would usually occur. By this arrangement the webs A and sections a are properly held at points below the arms and yet afforded 15 latitude of play without uncomfortably interfering with the stomach and back movements of the wearer, said play being promoted by the capacity of the button-tabs f' to slide relatively in engagement with their respective cords, thereby securing an automatic 20 adjusting effect at such points to comfortably conform to the body movements of the wearer.

It will be obvious that besides suspending the trousers in the manner stated the straps F may be disconnected from and connected 25 with the snap-hooks B D to permit the lowering and adjusting of the trousers without necessitating the removal of the wearer's coat and vest.

As the snap-hooks B D are comparatively 30 flat, their hooks proper may occupy an inside relation to avoid the catching of the outer garments thereon and without discomfort to the wearer.

The improved suspenders are highly effi-

cient, very simple and durable, and greatly 40 conduce to the comfort of the wearer and are totally unaccompanied by the familiar strains which tend to burst the buttons from their fastenings.

In Fig. 2 on the cord F between the button- 45 tabs f' and f'' is placed a sliding clasp h to engage the upper edge of the waistband of the drawers of the wearer.

Having now described my invention, what I claim as new, and desire to secure by Letters 50 Patent, is—

In suspenders, the web-sections A , each arranged to pass over the shoulder of the wearer to the front and to the back, and the end of each section terminating at a point below 55 his arm, snap-hooks B , and D , one on each of the lower ends of said web-sections, in combination with suspender-ends, having each two button-tabs, one on each end, and an intermediate cord, an intermediate button-tab 60 slidably engaging each of said cords and each of said cords detachably and slidably engaged, between said tabs, by the snap-hooks on the ends of said web-sections, and said cord by reason of such engagement holding said ends 65 apart and thereby affording facility for detaching said suspender-ends from said web-sections, and also affording facility for the said cord to slide in said snap-hooks, and in said intermediate button-tab.

In testimony that I claim the foregoing as my invention I have signed my name, in presence of two witnesses, this 28th day of July, 1902.

JOHN WILBER BURGETT.
